AUTOMATIC ELECTRIC SWITCH

William Wurdack, St. Louis, Mo., assignor to
 William Wurdack Electric Manufacturing Com-
 pany, St. Louis, Mo., a corporation of Missouri

Application October 12, 1931, Serial No. 568,379

14 Claims. (Cl. 200—89)

This invention relates generally to electrical apparatus. More particularly, my invention relates to a certain new and useful improvement in automatic electric switching apparatus.

5 My invention has for its prime objects the provision of a compact, inexpensive, and simple electrical switching apparatus especially, though not exclusively, suitable for use in connection with so-called branch-feeder circuits of house-
 10 wiring installations and the like; the provision, in such described apparatus, of a unique form of spring-biased switch-mechanism automatically operable for opening the circuit, as, for example, on occurrence of abnormal current-flow
 15 therein; the provision, in such apparatus, of means for manually manipulating the apparatus for opening and closing the circuit, said means, however, being "trip-free", that is, in-
 operative for circuit-closing purposes in the
 20 presence of abnormal current-flow conditions in the circuit; and the provision of a branch-cir-
 circuit cut-out incorporating circuit-protective fea-
 tures replacing the usual switch-and-fuse ar-
 rangement heretofore generally employed for
 25 such purposes.

And with the above and other objects in view, my invention resides in the novel features of form, construction, arrangement, and combination of parts hereinafter described and pointed 30 out in the claims.

In the accompanying drawings (three sheets),—
 Figure 1 is a side elevational view of an automatic electric-switch embodying my invention, the apparatus being shown in circuit-closing or
 35 "on" position;

Figure 2 is a side elevational view taken oppo-
 sitely to Figure 1 and approximately along the
 line 2—2, Figure 4;

Figure 3 is a vertical sectional view taken ap-
 proximately along the line 3—3, Figure 2, show-
 40 ing the switch-carrying spring-biased rocker;

Figure 4 is a top plan view of the switching ap-
 paratus;

Figure 5 is a fragmentary sectional plan view
 45 of the trip-magnet and its armature, taken ap-
 proximately along the line 5—5, Figure 1;

Figure 6 is a side sectional view similar to Figure 2, showing the apparatus in automatically tripped circuit-opening or "off" position with the switch-setting toggle in expanded operative position for re-setting the switch to circuit-closing position;

Figure 7 is a view similar to Figure 6, showing
 50 the switch-setting toggle knuckled in non-opera-
 tive position and the manipulating member or
 "handle" in trip-free position; and

Figure 8 is a view similar to Figure 2, show-
 ing the apparatus in partial switch-opening po-
 sition.

60

Referring now more in detail and by refer-
 ence characters to the drawings, which illustrate
 a preferred embodiment of my invention, A des-
 ignates a suitable base-plate preferably of insu-
 lation material, provided, in the present instance,
 65 with a pair of suitably attached front and rear
 depending legs 1, 2, respectively, for convenient
 mounting upon a panel-board or other support.
 Adjacent the front leg 1, the base A is provided
 70 with an aperture 3, and in the present instance
 the base A is shown with its opposite rear cor-
 ners side-marginally cut away, as at 4, 4' re-
 spectively.

Depending through the base A adjacent its
 rear margin, is a terminal-post or screw 5 hav-
 75 ing threaded securing engagement and conduct-
 ing relation on the under side of base A with an
 angular extension 6 of a fixed contact-blade 7
 projecting obliquely upwardly and forwardly in
 the cut-away or recessed base-portion 4, as best
 80 seen in Figure 1.

Projecting upwardly through the base A on
 its side margin forwardly of the cut-out 4, is a
 conducting-post or screw 8, and fixed flatwise on
 base A in conducting relation with post 8, is a
 85 strip 9 terminating in an obliquely upwardly
 and rearwardly projecting contact-blade 10 lon-
 gitudinally of the base A aligned with and spaced
 from the rear blade 7 for co-operation with the
 swingable or oscillatory blades of the switch, as
 90 presently appearing.

B designates the main frame of the apparatus,
 which is disposed longitudinally on the base A
 adjacent the contact-blades 7, 10, and comprises
 preferably a pair of rigid members or plates 11,
 95 12, permanently connected together in upstand-
 ing spaced parallel relation by suitable front
 and rear spacer-blocks 13, 14, respectively, suit-
 ably fixed to the base A, for frame-securing pur-
 poses, as by means of suitably elongated screws 100
 15 passed through the respective legs 1, 2, and
 base A for threadedly engaging the blocks 13, 14,
 as best seen in Figure 2.

Along their lower margins, the frame-plates
 11, 12, are suitably cut-away providing irregu-
 larly formed plate-edge bottom walls, as at a, b,
 respectively, the contours thereof being best seen
 in Figure 1. Formed in the plate-edge walls
 a, b, adjacent the rear of the frame B, are trans-
 versely registering re-entrant or inverted V-
 110

- shaped notches 16 having their apices disposed in a plane transversely bisecting the plane of the fixed blades 7, 10, and provided with suitably formed arcuate fulcrum seats 17, suitably adjacent to which the downwardly diverging opposite side walls of the notches 16 are provided with opposed front and rear arcuate stop-seats 18, 18', the rear side walls of the notches 16 being extended downwardly in approximately vertical relation to base A and the medial bisecting plane of the notches 16 extending forwardly and downwardly from the fulcrum seats 17, as best seen in Figure 2, where merely the frame-plate 11 is shown, the frame-plate 12, however, being similarly formed, as will be understood.
- C designates a U-shaped rocker-frame or double-crank for supporting the oscillatory switch-jaws of the apparatus, the rocker C being adapted for removable insertion through the cutout portions of the respective frame plates 11, 12, and including a crank-pin 19 and respective crank-arms 20, 21 extending angularly from the opposite ends thereof. Longitudinally spaced on the arms 20, 21, are pairs of inwardly presented opposed spacer-blocks 22, 23, and 22', 23', respectively, the blocks 22', 23', being riveted, as at 24, to the arm 21, and the blocks 22, 23, being secured to the arm 20 as will shortly appear.
- The opposing blocks 22, 22', are in transverse alignment suitably mounted at the ends of the respective arms 20, 21, and provided with axially reduced portions or fulcrum pins 25 adapted for rotarily engaging the fulcrum seats 17 in the notches 16 of the plates 11, 12.
- The opposing blocks 23, 23', are also in transverse alignment located intermediately of the respective arms 20, 21, and provided likewise with axially reduced portions or stop-pins 26 adapted for alternately impinging the opposite stop-pin seats 18, 18', in the walls of the notches 16 on oscillation of the rocker-frame or crank C on its fulcrum pins 25, as presently appearing.
- The blocks 22, 23, are provided with elongated rivet-shanks 27 passed through the arm 20 for projecting laterally therefrom over the base cut-out 4, and supported on the rivet-shanks 27 is a switch assembly D, which includes a pair of metal washers 28, between which is mounted a pair of insulation washers 29 spaced by means of insulation-thimbles 30 on the rivet-shanks 27. Mounted on the thimbles 30 and firmly gripped together and between the insulation washers 29 by riveting the shanks 27 over the outside washer 28, is a pair of hub-members 31, from which extend in suitable angular relation mating pairs of radial conducting arms 32 oscillatory in the vertical plane of the fixed blades 7, 10, about the axis of the fulcrum pins 25 as a center, and carrying endwise presented spaced co-operating pairs of jaws 33, 33', having oppositely flaring ears 33'' providing throat-like entrance to the space therebetween, the respective pairs of jaws 33, 33', being co-operatively adapted for sliding upon and conductively engaging the fixed contact-blades 7, 10.
- The switch D makes contact of its respective pairs of jaws 33, 33', with the blades 7, 10, for electrically connecting the latter through the conducting arms 32 and their hubs 31 as and when the rocker-frame C is rearwardly swung to approximately vertical or circuit-closing position with the stop-pins 26 in impingement with the rear stop-pin-seats 18', as best seen in Figures 1 and 2. However, when the rocker-frame C is forwardly swung for impinging the stop-pins 26 with the front stop-pin seats 18, the switch D is correspondingly oscillated in the present instance approximately 45 degrees to circuit opening position with the respective pairs of jaws 33, 33', wholly out of engagement with and substantially widely spaced from the also respective blades 7, 10, as best seen in Figures 6 and 7.
- Mounted between the frame-plates 11, 12, adjacent the base A and disposed preferably in the medial bisecting plane of the notches 16, as best seen in Figures 2, 6, 7, and 8, is a pintle 34, on which for rotatory movement intermediate the frame-plates 11, 12, is mounted at one end the lower arm 35 of an arcuate or irregularly curved substantially C-shaped generally rearwardly presented lever E adapted for oscillatorily embracing the rocker C.
- The lever E has spring-biased toggle-connection with the rocker C by means of a tensionally yieldable member or toggle-spring 36 pivotally, as by a spring-eye 36', attached at its lower end to the crank-pin 19 of the rocker C and at its upper end pivotally, as at 37, attached to the upper arm 38 of the lever E in such manner that the pivot-point 37 is shiftable with the lever E in toggle-knuckling manner from one side to the other of the line connecting the pivotal axes of the lever E and the rocker C.
- The lower arm 35 of the lever E is provided with a cam surface, as at 39, adapted for co-operation with the rocker C preferably by impinging the spring-eye 36' engaging the rocker-pin 19 for correspondingly shifting the rocker C from its described circuit-closing position on presently appearing forward swingable actuation of the lever E.
- By such arrangement, the rocker C will oscillate on its fulcrum 25 until the axis of the spring 36 is in registration with the axis of the fulcrum 25, as shown in Figure 8, whereby the switch D is initially moved for partial disengagement from the blades 7, 10, thus reducing the effort required for the final circuit-rupturing movement of the switch D.
- Hence, as the lever E continues its forward movement for shifting the axis of the spring 36 past the axis of the fulcrum 25, the tension of the stretched or tensionally expanded spring 36 becomes operative for "snapping" and rapidly, in a manner most effective for suppressing any occurring current-rupturing arc, spacing the jaws 33, 33', of the switch D from the blades 7, 10, the changing bias of the spring 36 thus causing the rocker C to complete its oscillatory movement to circuit opening position shown in Figure 6.
- Provided at its front end with a bifurcated head 40 pivotally connected, as at 40', to the upper arm 38 of the lever E, is a plunger 41 suitably reciprocable in and through the forwardly-presented open-end of a barrel 42. Mounted on the plunger 41 for compressive engagement between the head 40 and the rear wall of the barrel 42, is a yieldable member or spring 43, the barrel 42 having a rearwardly projecting lug 44 working in a suitable vertically slotted frame cross-member 45 supported by and between the frame-plates 11, 12.
- In circuit-closing position, the lever E and rocker C are both disposed in extreme rearwardly swung positions, as best seen in Figure 2, such that the spring 36 is obliquely disposed wholly to the rear of the line connecting the rocker-fulcrum 25 and lever-pintle 34, the tensional pull of the spring 36 thus biasing the lever E yield-

ingly upon the plunger-spring 43 and the rocker C upon the rear stop-seats 18.

The lever E is endwise tensionally influenced, however, by the plunger-spring 43, which is of ample strength for the purpose, for overcoming the pressure of the lever-spring 36 for normally propelling the lever E forwardly toward circuit-opening position, the lever E and rocker C then being both disposed in extreme forwardly swung position, with the spring 36 disposed wholly forwardly of the line connecting the fulcrum 25 and pintle 34, as best seen in Figure 6.

On the underside of the upper lever-arm 38 is provided a stop-seat 46 adapted for impinging a stop-bar 47 mounted in and between the frame-plates 11, 12, in such position as to arrest the lever E when in its extreme forward circuit-opening position, the tensional pull of the spring 36 biasing the lever E upon the stop 47 and the rocker C, in turn, upon the front stop-seats 18.

Disposed forwardly in the frame B, is a manipulative member F comprising an approximately circular body-member or disc 48 pivotally mounted for oscillatory movement on a shaft 49 supported suitably by and between the frame-side members 11, 12. Upon its rearwardly-presented side, the disc 48 is suitable chordally cut-away, as shown, and provided with a pair of arm-like radially projecting suitably spaced registering ears 50, for purposes presently appearing. Projecting upwardly from the disc 48, is a radial handle 51 adapted to be forwardly and upwardly inclined when in circuit-closing position, as in Figure 2, and to be rearwardly and upwardly inclined when in circuit opening position, as shown in Figure 6, the peripheral portions of the disc 48 adjacent the handle 51 being conveniently adapted to carry suitable indicia, one such being shown as at 52 in Figure 4, for indicating the condition of the switching-apparatus.

The manipulative member F is operatively connected for switch-setting purposes with the lever E by means of a spring-set secondary toggle-mechanism G, which includes a link 53 composed of a pair of spaced side members pivotally connected at their rear end, as at 54, to the upper arm 38 of the lever E, the members of the link 53 being suitably cut away on their under side, as at 55, for clearing the stop-bar 47. At their forward end, the members of the link 53 are preferably integrally connected together by a depending U-shaped stirrup 56, which, in turn, carries a knuckle pin 57 to which is foldably jointed or pivotally connected one end of a link 58 having its other end pivotally, in turn, by a primary knuckle-pin 59, connected to the ears 50 of the member F.

The stirrup 56 carries a lateral lug 60, upon which bears one end of a torsional spring 61 mounted or coiled on the laterally projecting end of the pin 57. At its other end, the spring 61 is engaged with a pin 62 laterally projecting from the link 58, the latter being of such dimensions and being so biased by the spring 61 as to normally impinge the bight of the stirrup 56 with the axis of the pin 57 disposed in toggle-locking manner substantially above a line connecting the end pivots 54 and 59 of the toggle-links 53, 58, respectively, thereby establishing a toggle-locking effect through the upwardly curved line of pressure action connecting the points 54, 57, and 59, which toggle may be broken, however, by downwardly flexing the links 53, 58.

The several parts of the apparatus are of such relative dimensions that, when the toggle G is in

its described locked and extended position, rotary movement of the member F for rearward swinging actuation of the ears 50 will correspondingly rearwardly shift the toggle G and through the toggle G push or exert pressure endwise on the lever E with ensuing rearward actuation of the lever E until the latter is in final circuit-closing position. At such time, the pin 59, which suitably for such purpose projects laterally from the ears 50, impinges the wall b of the frame-plate 12 for limiting the oscillation of the member F, such that the axis of rotation thereof, that is to say, the shaft 49, will then lie below the projection of a line connecting the toggle-pivots 54, 59, thus establishing a primary toggle-effect through the upwardly curved line of action connecting the points 54, 57, 59 and 49, for locking the lever E in circuit closing position against the pressure of the plunger-spring 43. Such toggle-effect may be tripped or broken and the constraint upon shifting movement of the lever E removed normally by manually reversely rotating the member F, but the switch may be tripped also by applying downward pressure on the link 58 for reversely rotating the member F or for breaking the secondary toggle G if the member F is held against rotation, as presently appearing.

H designates an automatic electro-responsive mechanism for applying such toggle tripping pressure on the link 58 of the toggle G, said mechanism including a vertically shiftable trip-bar 63 having at its upper end a laterally projecting lug or detent-finger 64 adapted for engaging the link 58 on downward shifting actuation of the bar 63 for folding and breaking the toggle G from its described circuit-closing and expanded position.

Preferably the bar 63 is provided intermediate its ends with a longitudinal slot 65 whose walls have sliding engagement with a pin 66 projecting from the frame-plate 11, the finger 64 being engageable by the link 58 for normally freely liftingly shifting the bar 63 as the toggle G rises to circuit-closing position.

At its lower end, the bar 63 depends through a slot 67 provided in the base A (Figure 5) and is pivotally connected, as at 68, to the rearwardly projecting approximately horizontally disposed arm of a bell-crank armature 69 pivotally supported, as at 70, from the upper leg of a rearwardly presented horizontally disposed U-shaped magnet core 71 of an electro-magnetic winding 72, the core 71 being supported from and between suitably depending portions of the frame side-members 11, 12, as best seen in Figures 1 and 6.

The lower leg of the core 71, which supports the winding or coil of the magnet 72, terminates in an oblique-ended pole 73 complementary to the similarly shaped end 74 of the approximately vertically depending arm of the armature 69, the armature-end 74 being normally operatively spaced from the pole 73 through the lifting action exerted on the bar 63 through its finger 64 by the link 58 when the switch is in closed or "on" position.

At one end, the magnet winding 72 is connected by a lead 75 with the contact 10 through its post 8, and at its other end, the winding 72 is connected by a lead 76 to a terminal post 77 mounted through the base A forwardly of the post 8 and having threaded securing engagement with a suitable line-terminal-lug 78. Preferably the lug 78 is suitably connected with the circuit-branch-wire 79, while the circuit feed-wire 80 is connected with the terminal-post 5 of the fixed contact-terminal 7.

Connected between the posts 8 and 77, and hence in parallel with the magnet winding 72, is a shunt 81 having a rising-temperature characteristic, such that the shunt 81 offers negligible resistance to normal current-flow for hence substantially short-circuiting the magnet winding 72. However, the shunt 81 offers increasing resistance to increasing current-flow such that, at a predetermined abnormal or excessive current-flow, the resistance will cause a portion of such abnormal current-flow to pass through the magnet-winding 72 for energization thereof sufficiently for attracting the armature-end 74 to the magnet pole 73, thereby oscillating the bell-crank 69 for downward actuation of the bar 63 for impinging the bar-carried detent 64 with toggle-breaking effect upon the link 58, flow of current through the winding 72 taking place only when the apparatus is in circuit-closing position.

In use and operation, the apparatus being in circuit-closing position as shown in Figures 1 and 2, manual manipulation of the apparatus to circuit-opening position may be effected by rearwardly swinging the handle 51 with ensuing lowering movement of the ears or arm 50 until its carried primary knuckle pin 59 crosses the line of toggle action connecting the points 54, 49, thereby breaking the primary toggle effect and releasing the toggle locking constraint upon the lever E, which is then actuated by the plunger-spring 43 to circuit-opening position.

Ensuing upon such actuation of the lever E, the lever-cam-surface 39 bears upon the crank-pin 19 of the rocker C, thereby forwardly shifting the same about its fulcrum 25 until the spring 36 passes the rocker-center, whereupon the increased tension of the now stretched or expanded spring 36 becomes operative for rapidly and with a "snapping" effect shifting the rocker C to final circuit-opening position, the spring 36 then being disposed, as described, wholly forwardly of the line connecting the rocker-fulcrum 25 and lever-pintle 34 for biasing the rocker C upon the front rocker-stop-seats 18. Meanwhile the switch D, which in circuit-closing position makes connecting and conducting contact with the switch-blades 7, 10, is by and with such forward actuation of the rocker C caused initially to approach terminal-disconnecting position, as shown in Figure 8, whereupon correspondingly to the spring-snapped actuation of the switch-carrying rocker C, the jaws 33, 33', of the switch D are, most effectively for arc-severance and suppressing purposes, suddenly and widely spaced and disconnected from the blades 7, 10, as shown in Figure 6.

Under propelling influence of the plunger-spring 43, the lever E continues its forward movement until the lever-stop 46 impinges the frame stop-bar 47. During the forward movement of the lever E, its connected toggle G is constrained by the knuckle torsion spring 61 to remain in its switch-setting operative position, that is, in substantially rigid toggle-locked position, whereby the co-operating links 53, 58, act as a unitary or non-flexing member for transmitting the movement of the lever E to the member F, thereby rotating the latter to "off" position with the handle 51 rearwardly inclined, the several parts of the apparatus being then disposed as shown in Figure 6.

From its circuit-closing position, as shown in Figures 1 and 2, the apparatus may also be automatically "tripped" responsively to abnormal current flow, which, as has been described, re-

sults in the application of toggle-breaking pressure upon the link 58 with ensuing rotative effect, through pin 59 and arm or ears 50, upon the member F, the expanded and locked toggle G meanwhile pivoting upon the lever-pin 54 until the primary knuckle pin 59 crosses the line of toggle action connecting the points 54, 49, thereby releasing the apparatus for movement to its circuit-opening position, as shown in Figure 6, as previously fully set forth.

Whether manually or automatically "tripped" to its circuit-opening or "off" position, as in Figure 6, the apparatus may with ease and facility be restored to circuit-closing or "on" position by simply forwardly swinging the handle 51 and thereby rotating the member F, which movement to the member F, being communicated through the rigid or locked toggle G to the lever E, correspondingly rearwardly shifts the latter against the pressure of the plunger spring 43, the lever E taking its final rearward position as the rotary movement of the member F shifts its carried pin 59 above the line connecting the points 54, 49, thus in toggle-like manner retaining the lever E in its circuit-closing position against the tension of the plunger spring 43.

As the lever E is thus rearwardly shifted, the spring 36 crosses the center of the rocker C, whereupon the latter is suddenly "snapped", by reason of the increased tensional effort of the now stretched or expanded spring 36, to circuit-closing position, the spring 36 then residing wholly rearwardly of the line connecting the rocker-fulcrum 25 and lever-pintle 34, for biasing the rocker C upon the rear rocker stop seats 18.

Such actuation of the rocker C restores the switch D to conducting or circuit-closing contact with the blades 7, 10, the flared ears 33' of the pairs of jaws 33, 33', providing easy guiding entrance of the blades 7, 10, therebetween, most desirable in view of the extremely rapid movement of the switch D to circuit-closing position.

However, if the apparatus is moved to such circuit-closing position against an abnormal condition existing in the switch-connected circuit, such as to cause an excessive current flow therethrough, the shunt 81 will with substantially negligible time lag divert sufficient current to the magnet 72 for actuating the trip-bar 63 as described.

Under such conditions, the member F is "trip-free", that is to say, if the handle 51 is manually shifted to and held in "on" position, the actuation of the trip bar 63 is nevertheless effective for breaking or knuckling the toggle G to non-operative position, the link 58 in this case rotating about the now stationary pin 59 and the link 53 rotating on the pin 54 for flexing or folding the toggle G about its knuckle 57, thereby releasing the lever E for movement of the apparatus to circuit-opening position as described, the parts then being disposed as clearly shown in Figure 7.

It will be seen that the link 58 now depends in inverted position from the pin 59, and hence, before the apparatus may again be actuated for closing the circuit, it is necessary to first move the handle 51 and member F to "off" position, thus unfolding or expanding the toggle-members 53, 58, which under bias of the spring 61, snap into extended toggle-locked position, the apparatus being then fully restored to the "off" position shown in Figure 6.

My new switch has been found exceedingly

efficient in use and operation. It is composed of relatively sturdy and inexpensively manufactured parts, which may be most readily and conveniently assembled, and the switch as a whole is compact, durable, and highly efficient and reliable in the performance of its intended functions.

It will be understood that changes and modifications in the form, construction, arrangement, and combination of the several parts of the apparatus may be made and substituted for those herein shown and described without departing from the nature and principle of my invention.

Having thus described my invention, what I claim and desire to secure by Letters Patent is,—

1. In an electric-switch, in combination, spaced conducting blades, an upstanding support in fixed relation to the blades, a frame mounted for rocking movement on the support, blade-engaging jaws on the frame, means including an arcuate lever having upper and lower arms and pivot-connection at its lower arm with the support and a spring attached to the lever and frame and co-operable with the lever for rocking the frame for carrying the jaws into and out of circuit-closing engagement with the blades, and means for yieldingly urging the frame to, and retaining the frame in, circuit-opening position, said last means including a spring-pressed plunger mounted for rocking and reciprocatory movement on the support and pivotally connected at an end to the upper arm of the lever for endwise exerting actuating pressure on the lever longitudinally of the support.

2. In an electric-switch, in combination, spaced conducting blades, an upstanding support in fixed relation to the blades, a frame mounted for rocking movement on the support, blade-engaging jaws on the frame, means including an arcuate lever having upper and lower arms and pivoted at its lower arm upon the support and a spring attached to the lever and to the frame and co-operable with the lever for snapwise rocking the frame for carrying the jaws into and out of circuit-closing engagement with the blades, and means co-operable with the frame-rocking means for yieldingly urging the frame to, and retaining the frame in, circuit-opening position, said means including a barrel mounted for rocking movement on the support, a plunger reciprocable in and relatively to the support rockable with the barrel and pivotally connected at an end to the upper arm of the lever, and a tensional member seated in the barrel for compression by the plunger when the frame is in actuated to circuit-closing position.

3. In an electric-switch, in combination, spaced conducting blades, a support in fixed relation to the blades, a frame mounted for rocking movement on the support, blade-engaging jaws on the frame, means including a pivoted lever for yieldingly rocking the frame for carrying the jaws into and out of circuit-closing engagement with the blades, means on the support for exerting pressure endwise on the lever for yieldingly urging the frame when in circuit-closing position to circuit-opening position, and means for opposingly exerting pressure endwise on the lever for yieldingly maintaining the frame in circuit-closing position against the influence of said frame-urging means.

4. In an electric-switch, in combination, spaced conducting blades, a support in fixed relation to the blades, a frame mounted for rocking move-

ment on the support, blade-engaging jaws on the frame, means including a pivoted lever for yieldingly rocking the frame for carrying the jaws into and out of circuit-closing engagement with the blades, means on the support for exerting pressure endwise on the lever for yieldingly urging the frame when in circuit-closing position to circuit-opening position, and toggle mechanism for opposingly exerting pressure endwise on the lever for yieldingly maintaining the frame in circuit-closing position against the influence of said frame-urging means.

5. In an electric-switch, in combination, spaced conducting blades, a support in fixed relation to the blades, a frame mounted for rocking movement on the support, blade-engaging jaws on the frame, means including a pivoted lever for yieldingly rocking the frame for carrying the jaws into and out of circuit-closing engagement with the blades, means on the support for exerting pressure endwise on the lever for yieldingly urging the frame when in circuit-closing position to circuit-opening position, toggle mechanism for opposingly exerting pressure endwise on the lever for yieldingly maintaining the frame in circuit-closing position, and means for knuckling the toggle for removing the constraint thereof on the frame-urging means.

6. In an electric-switch, in combination, spaced conducting blades, a support in fixed relation to the blades, a frame mounted for rocking movement on the support, blade-engaging jaws on the frame, means including a pivoted lever for yieldingly rocking the frame for carrying the jaws into and out of circuit-closing engagement with the blades, means on the support for exerting pressure endwise on the lever for yieldingly urging the frame when in circuit-closing position to circuit-opening position, toggle mechanism including yieldingly foldable members for opposingly exerting pressure endwise on the lever for yieldingly maintaining the frame in circuit-closing position, and means for knuckling said foldable members for removing the constraint of the toggle mechanism on the frame-urging means.

7. In an electric-switch, in combination, spaced conducting blades, a support in fixed relation to the blades, a frame mounted for rocking movement on the support, blade-engaging jaws on the frame, means including a lever having pivot-connection with the support for yieldingly rocking the frame for carrying the jaws into and out of circuit-closing engagement with the blades, means on the support co-operable with the frame-rocking means for yieldingly urging the frame when in circuit-closing position to circuit-opening position, toggle mechanism co-operable with the frame-rocking means in opposition to the frame-urging means for yieldingly maintaining the frame in circuit-closing position, said toggle mechanism comprising an arm pivotally mounted on the support and foldably connected members spring-set for operatively linking the arm with the lever, and means comprising a member shiftable for engagement with the foldably connected members for flexing the same relatively to the arm and the lever for knuckling the toggle for removing the constraint thereof on the frame-urging means.

8. In an electric-switch, in combination, spaced conducting blades, a support in fixed relation to the blades, a frame mounted for rocking movement on the support, blade-engaging jaws on the frame, means including a lever having pivot-con-
